UNITED STATES PATENT OFFICE.

LEWIS LARCHAR, OF MARBLE ROCK, IOWA.

RAILWAY-TRACK CLEARER.

SPECIFICATION forming part of Letters Patent No. 309,632, dated December 23, 1884.

Application filed April 26, 1884. (No model.)

To all whom it may concern:

Be it known that I, LEWIS LARCHAR, of Marble Rock, in the county of Floyd and State of Iowa, have invented a new and Improved 5 Railway-Track Clearer, of which the following is a full, clear, and exact description.

The object of my invention is to provide a simple, effective, and durable device for clearing snow and ice from railway-tracks.

10 The invention consists in a stock having a pivotal and spring connection with the engine or car, and a foot-block carrying the clearer plates or cutters pivoted to the stock to swing forward and backward, said block being held 15 in normal working position by springs at its opposite faces, and so as to yield to pass obstructions.

The invention consists, also, in constructions and combinations of parts of the clearer 20 to allow it to swing laterally to accommodate the cutters to the movements of the car and the line of the track, and also to permit the cutter-carrying foot to be held raised from the track, all as hereinafter fully described and 25 claimed.

Reference is to be had to the accompanying drawings, forming part of this specification, in which similar letters of reference indicate corresponding parts in all the figures.

30 Figure 1 is a perspective view of my improved track-clearer in position for use on one rail of the track. Fig. 2 is a side elevation, with the foot of the clearer in section; and Fig. 3 is a front elevation.

35 The letter A indicates the stock or upper portion of the clearer, to which the foot or block B is pivoted at *a*, so as to swing on the stock toward the front or rear. The stock A is pivoted at *b* in lugs or plates *c c* on the 40 frame of the engine, or on a cross-bar, C, attached thereto of the locomotive engine or railway-car frame, and so as to swing the stock A on the pivot *b* from side to side to accommodate the side swing of the engine or car on 45 rough tracks or in rounding curves, the side motion of the stock being limited by lugs *a' a'* on bar C. Opposite springs, D E, fixed at the front and rear faces of the stock A, bear upon corresponding faces of the foot-block B, to hold 50 it in line with the stock, and with sufficient power to resist the strain on the clearer-plate F of block B in removing the snow or ice from

the top face of the rail O, and to resist also the strain on the cutter-bar or groover G, which is fitted in the block B, and acts along the inside of the rail O, to remove the snow or ice packed on the rail and afford a clear passage for the flanges of the car-wheels. The tension of the springs D E is, however, so regulated that if either the plate F or cutter-bar G or 55 the block B comes in contact with any unyielding substance or obstruction the block B will swing either backward or forward on its pivot *a*, accordingly as the engine or car to which the clearer is attached in moving forward or backward, and thus avoid damage to the engine or car or to the clearer itself, and when the obstruction is passed the springs D E will promptly shift the block B to its 60 upright working position.

As it is desirable at times to hold the block B raised out of contact by its plate and bar F G with the track, I propose to cut a slot or mortise, H, through the block, into which the spring D may pass when the block is swung 65 upward on pivot *a*, as in dotted lines in Fig. 2, said spring D then acting against the walls of the slot H to hold the block in raised position, as will readily be understood; or, if desired, the block may be held up by a hook 70 fixed to the car-body or truck-frame in any suitable manner for operation by the engineer.

I make the clearer-plate F in the form of a small curved mold-board plow, so that it shall throw the snow and ice from the head of the 75 rail entirely clear of the rail, and the plate F may be attached by bolts *f*, or in any convenient manner to provide for its renewal and for adjustment vertically and laterally on block B, as shall be required for its best action.

The cutter-bar G, here shown held to place in the block B by the flat staple or clip *g* entering a notch of the cutter and driven into the block, may be held to the block in any approved way, permitting its adjustment for taking up the wear, and a renewal of the cutter when worn out.

If desired, springs I may be fixed to bear at the side faces of the stock A, (see Fig. 3,) for holding it normally in a vertical position sideways, but so as to yield or swing either way on pivot *b*, to accommodate the shoe B to the swing of the car or the line or curvature of the track.

At *h* is shown a staple or clip, which crosses the slot or groove made in the block *B* to receive the tongue of the stock *A*, said clip *h* serving to strengthen block *B* and also as a wear-plate, against which the narrow lower end of the spring *D* acts.

It will be understood that one of the track-clearer devices will be applied at each rail and suitably connected together to act upon both 10 rails of the track at once.

I do not limit myself to the precise means shown of connecting the clearer to the engine or car, or to the particular form and connection of the springs, as the details of construction may vary within the scope of my invention.

Having thus described my invention, I claim as new and desire to secure by Letters Patent—

1. The combination, in a track-clearer, of 20 the stock *A*, having a pivotal and spring connection with the engine or car, and having a

clearer-plate or cutter-carrying foot, *B*, pivoted to it to swing both forward and backward, and springs for holding the foot *B* normally and yieldingly in line with the stock 25 *A*, substantially as shown and described.

2. The combination, in a track-clearer, of the stock *A*, hung from the engine or car so as to swing laterally, of the pivoted foot *B*, carrying the clearers or cutters, and of springs 30 for holding the foot normally and yieldingly in line with the stock *A*, substantially as shown and described.

3. The combination, with the stock *A* and pivoted foot *B*, slotted at *H*, of the spring *D*, 35 adapted to enter the slot for holding the foot raised, substantially as herein shown and described.

LEWIS LARCHAR.
